OVERSHOE SKID

Filed Feb. 18, 1927

Inventor:
Joseph S. Capen
by Harry Smith, Harry Hines.

UNITED STATES PATENT OFFICE

JOSEPH S. CAPEN, OF STOUGHTON, MASSACHUSETTS

OVERSHOE SKID

Application filed February 18, 1927. Serial No. 169,359.

This invention relates generally to boots and shoes but particularly to a novel skid device for more conveniently and safely slipping boots or shoes, and particularly those with rubber heels, into overshoes or rubbers. Heretofore no great difficulty has been experienced in so doing, owing to the fact that the leather heels, unless wet, were not likely to cause substantial friction when brought into contact with the rubber or cloth lined inner wall or lining of the ordinary rubber or overshoe. With the very general use of the rubber heel, or rubber top lift, it has been found that the friction of the sides and back of the heel of the shoe against the rubber or cloth lining of the rubber or overshoe, when slipping the former into the latter, is such as to make it an extremely inconvenient task and the practice tends strongly to tear the back of the rubber or overshoe. My invention aims particularly to overcome this difficulty.

In the drawings illustrating one embodiment of my invention selected for illustration and description,

Fig. 1 is a plan;

Fig. 2, a side elevation;

Fig. 3, a forward end elevation from the right, Fig. 2;

Fig. 4, a plan of a modified form of construction;

Fig. 5, a development thereof;

Fig. 6, a side elevation of this form in a round package or roll for convenient sale and handling of the same;

Fig. 7, a plan of a second modification;

Fig. 8, a vertical longitudinal section on the line 8-8, Fig. 7;

Fig. 9, a development thereof;

Fig. 10, a detail plan of the end of the collar construction of Fig. 7, bent inwardly to engage the breast of the heel;

Fig. 11, a plan of still another form of construction; and

Fig. 12, a plan of a simple, yet useful, form of construction.

Referring first to Figs. 1 to 3 inclusive, my novel construction which may be termed an overshoe collar or skid comprises a curvilinear strip *a* of any suitable material, such as

thin metal, cardboard, stiffened paper, celluloid, or indeed of almost any nature that will serve to eliminate the friction usually created by the slipping of the shoe heel, particularly if of rubber, into the rubber or overshoe.

This curvilinear member *a* preferably comprises a seat flange 1 which may be of any desired width, with a side flange 2 of any convenient height, but preferably high enough to cover the rubber portion of the heel. This skid or collar is preferably die cut and formed of horseshoe shape and fashioned narrower at its forward ends than the heel on which it is to be used, so that when the skid is slipped onto the bottom of the heel, its ends will need to be sprung apart slightly, and thus give them a tendency to hug closely the sides of the heel and assist in keeping the skid in position on the heel.

The skid *a*, Fig. 1, may be provided with a rubber or other band 3, the opposite ends of which are secured in the ends of the upstanding flange 2 and after the skid has been slipped over the lower lift of the heel, the band 3 may be carried forwardly and about the breast 4 of the heel, as shown in Fig. 1 in dotted lines, and thereby serve as one form of retaining means to assist in holding the curvilinear member or skid in place.

After the skid *a* has been placed in position upon the lower lift of the heel, the heel of the shoe readily may be slipped into a rubber or overshoe without difficulty, or danger of tearing or unduly straining it, because the smooth surface of the skid positioned between the rubber heel and the inner wall of the rubber or overshoe eliminates practically all friction between the two members.

In Fig. 4 I have illustrated a modified form of my invention wherein the seat flange 1 of the skid is crimped or corrugated to give it the necessary shape to properly fit the shoe heel. When it is desired to use such a member, it may be placed readily upon the top lift of the heel as before, and, as with the form, Fig. 1, if made sufficiently resilient and of correct size, will retain itself in position without any retaining means.

Or, as in Fig. 5, the member conveniently may be made in the form of a strip 5. This

readily may be done by taking a strip of material 5, crimping it crosswise throughout its length by any suitable means and in any suitable form, and then scoring the same longitudinally at 6, where it conveniently may be bent to form the upstanding flange 2.

When it is desired for use, a strip of sufficient length is torn off, one edge 7 stretched, thereby removing the greater part of the 10 crimping effect along that edge and expanding the same sufficiently to enable it to extend around the outside of the heel. After the strip edge has been stretched, it may be folded readily to form the flange 2 by bending 15 the lower portion of the strip along the line 6, as stated. This strip, Fig. 6, conveniently may be made and assembled in roll form 8, for commercial handling, a strip of the desired length being torn from the roll when 20 needed, as explained.

In Fig. 7 I have illustrated still another form wherein the seat flange 1 is serrated to leave spurs 9 which serve excellently as a substitute for the continuous flange illustrated in Fig. 1. This form, see Fig. 9, also readily may be made in strip form, scored along the line 10, and sold and handled commercially in the form of a roll 8, as in Fig. 6. When desired for use, a strip of sufficient 25 length is torn from the roll, the side flange portion 2 bent relatively to the seat teeth 8 along the line 10.

When using the form illustrated in Fig. 7, the end teeth 9 may be bent up parallel with 30 and against the inner face of the upright flange 2, and then, see Fig. 10, the end portions of the upright flange with the teeth 9 laid against them are together folded inwardly at right angles to the flange as a whole so 35 that the bent ends will lie against and embrace the corners of the breast of the heel to which the device is applied and thus assist in holding the device in place upon the heel in much the same manner that the elastic cord 3 acts in the form illustrated in Fig. 1. Or if preferred, see Figs. 4 and 7, portions of the 40 strip shown in Figs. 5, 9, which will form the upright flange 2 may be provided at intervals with punched or cut tabs or ears 12 which 45 may be bent inwardly to constitute other forms of retaining means to engage the breast of the heel to assist in holding the skid in position preparatory to or while in use.

In Fig. 11 there is shown a modification 50 comprising a flat seat 13 for the heel with a corrugated upright flange 2. The seat 13 is slit at 14 to render it more expandible and contractible as to size with respect to the heel of the shoe.

In Fig. 12, I have illustrated a useful modified form comprising a strip of suitable 55 material scored crosswise at a suitable point for bending. After slipping the portion 15 beneath the heel, the portion 16 will fold upward against the back portion of

the heel and so fall between the heel and the outer shoe lining and by thus eliminating frictional contact between the heel and lining, cause the shoe more readily to slide into the overshoe.

By the use of my novel overshoe skid the 70 difficulty in applying overshoes and rubbers to shoes having rubber heels and top lifts, above referred to, is entirely avoided.

My invention is not limited to the embodiments herein shown and described. 75

Claims:

1. A shoe heel skid comprising a pliable perishable curvilinear strip with an upstanding flange conformable to fit heels of different sizes and shapes. 80

2. A shoe skid comprising an upstanding flange with seat forming teeth at one edge conformable to fit heels, their top lifts and breasts of different sizes and shapes. 85

3. A shoe skid comprising a pliable curvilinear strip with an upstanding flange having an ear thereon.

4. A shoe skid for heels comprising a strip of flexible material with a toothed edge, 90 and marked longitudinally at the line of the edge of the outer heel lift.

5. An open front resilient heel-edge-cover 95 adapted to be slid onto the heel from the back and comprising an upstanding side covering and gripping portion to embrace and grip the side of the heel in the vicinity of the top and an attached heel-top-covering margin serrated to permit opening and closing of the cover to fit different heels. 100

6. An open front resilient heel-edge-cover 105 adapted to be slid onto the heel from the back and comprising an upstanding side covering and gripping portion to embrace and grip the side of the heel in the vicinity of the top, an attached heel-top-covering margin serrated to permit opening and closing of the cover to fit different heels and fastening means near the ends of the cover 110 adapted to engage the breast of the heel to aid in holding the cover in position.

In testimony whereof, I have signed my name to this specification.

JOSEPH S. CAPEN.
